UNITED STATES PATENT OFFICE.

ROBERT HARVEY McDOWELL, OF ALLIANCE, OHIO, ASSIGNOR TO THE ELECTRIC FILTER COMPANY, OF ALLIANCE, OHIO, A CORPORATION.

AUTOMATIC ELECTRICAL CUT-OFF.

No. 853,990.

Specification of Letters Patent.

Patented May 21, 1907.

Application filed May 26, 1905. Serial No. 262,506.

To all whom it may concern:

Be it known that I, ROBERT HARVEY McDOWELL, a citizen of the United States, residing at Alliance, in the county of Stark and State of Ohio, have invented a new and useful Improvement in an Automatic Electrical Cut-Off, of which the following is a specification.

This invention relates to an automatic cut-off or circuit breaker, for use in connection with a purifier and filter, described in a separate application, and combines a valve cut-off, for controlling the discharge of a fluid from a filtering chamber and the simultaneous making and breaking of an electrical circuit.

In the purifier and filter with which this invention is used the liquid before being passed to the filtering chamber is subjected to the action of an electrical circuit and such action if maintained, will result in the boiling of the water and injury to the filtering stone employed in the filter.

The object of the present construction is to provide means whereby electrodes employed in the purifier are placed in an electrical circuit only when liquid is being drawn from the filtering chamber and the circuit broken as soon as the flow of liquid is stopped. This has formerly been accomplished by providing a suitable switch adjacent the device, which switch was intended to be operated to break the circuit when a sufficient amount of liquid had been drawn from the filter, but it has been found that the party drawing off the liquid failed to open the switch after shutting off the faucet and the current being left on, more or less damage has been caused.

This invention consists of the combination with a discharge faucet with an electrical switch having its operative part connected to the valve operating means of the faucet whereby the electrical circuit is broken when the valve is closed, and completed when the valve is opened.

In the accompanying drawings:—Figure 1 is a vertical side elevation with a portion of the faucet shown in section. Fig. 2 is a plan view of the fixed portion of the switch. Fig. 3 is an inverted plan view of the movable portion of the switch. Fig. 4 is an inverted plan view of the fixed portion.

In these drawings A represents a portion of a filter chamber carrying a discharge pipe A',

into the outer end of which is threaded a faucet or bib B, which has a valve seat B', formed at its inner end. A suitable valve C is placed in the pipe A' and is adapted to contact with the seat B'.

The bib or faucet B has an upwardly extending projection D over which is threaded a cap D' and the projection D is provided with an interior annular shoulder D². A cylindrical block or shaft E rotates within the projection D and bears upon the shoulder E². The block or shaft E is provided with a reduced portion E' which extends downwardly below the shoulder D² into the body portion of the faucet B.

A stem E² extends upwardly from the block E and on the axial line of the said block and through the cap D', and is provided at its upper end with a suitable handle E³ by means of which the stem and block may be rotated. A suitable angled shaft F is connected at its upper end eccentrically to the bottom of the extension E' of the block E and extends downwardly through the lower wall of the bib or faucet and has its lower end portion fitted into a semi-circular opening G formed centrally in a flanged disk G'.

The disk G' is formed of hard rubber or other suitable insulating material and a semi-circular brass contact plate G² is secured to the under side of the disk resting within and bearing upon the flange. The space between the ends of the said contact plate G² are bridged by a suitable insulator G³ which also rests within and against the depending flange of the disk G'. This forms a movable part of the switch and the stationary part is formed to a suitable disk H also of insulating material having a central circular raised portion H² around the greater portion of which extends a contact plate H² and between the ends of said plate and spaced from each end is a short curved contact plate H³. Suitable binding posts H⁴ are carried by the disk H and electrical conductors H⁵ lead from the said binding posts.

On the under side of the disk H is formed a transverse ridge H⁷ having a longitudinal bore therethrough and a metal rod of wire H⁶, has one end fitted into the bore of the ridge H⁷ and its opposite end fitted into a suitable perforation or socket formed in the filter chamber A, and intermediate its ends

the said wire or rod is bent to form a loop H^8 which serves as a support for the conductors H^6 as shown in Fig. 1.

To the valve C is connected a valve stem 5 J, which works through a suitable web J', and is pivotally connected to the shaft F. The flanged disk G' fits down over the central raised portion H' of the disk H and also over the contact plates H^2 and H^3 and the inner face of the contact plate G' slides upon outer faces of the contact plates or rings H^2 and H^3 .

It will be noted from Fig. 2 that one of the binding posts H^4 , is in electrical contact with 5 the contact plate H^3 and the other binding post H^4 is in contact with the semi-circular ring H^2 . The parts are so assembled that when the handle E' is thrown into such a position that the valve C is drawn to its seat, 10 each of the spaces between the plate H^3 and H^2 will be bridged by the insulating strip G^3 , but whenever the handle is turned so as to move the valve C away from its seat, the contact plate G' will be in engagement with the 15 plate H^3 , and at least one of the end portions of the contact plate H^2 bridging one of the spaces between the contact plates H^2 and H^3 , thus completing the circuit between the two binding posts H^4 .

30 It will be obvious that the rod H^6 not only serves as a support for the disk H but also prevents rotation of the same when the disk G' is rotated. In operation whenever a liquid is being drawn from the filter an electrical 35 circuit will be established between the binding posts H^4 and a current will be permitted to pass over the conductors H^5 to certain electrodes in a purifying chamber which electrodes, together with the electrical circuit 40 are shown and described in a separate application.

It will be further noted that the wire H^8 is connected to the body of the filter and that the movable member of the switch is carried 45 by the faucet or bib, and the latter is carried by the top or cover of the filter. When therefore the top of the filter is removed the stationary part of the switch to which the wires are connected is not disturbed by removing 50 either the top of the filter or the faucet.

Having thus fully described my invention, what I claim as new and desire to secure by Letters Patent, is:—

1. In combination with a faucet, a valve therein, an angled rod arranged transversely 55 in the faucet, and extending outwardly and downwardly, an electrical switch operated by said rod, a hand lever adapted to rotate said rod, and means connecting the valve to the rod. 60

2. A device of the kind described comprising a faucet, a valve, a valve stem, said faucet having a covered projection, a shaft therein having a reduced portion extending into the body of the faucet, a stem carried by the 65 shaft, a handle thereon, an angled shaft connected at its upper end eccentrically to the shaft end, the angled shaft extending downwardly through the lower wall of the faucet, the valve stem being pivoted to said angled shaft, and electrical circuit making and breaking means operatively connected to the lower end of the angled shaft. 70

3. A device of the kind described comprising a switch having a stationary portion, a 75 cut contact ring carried thereby, a contact plate arranged between the ends of the ring and spaced therefrom, a rotatable disk having a segmental contact plate adapted to slide upon the outer face of the contact plate 80 carried by the fixed portion, a discharge faucet having a valve therein, a crank shaft having one end connected to the rotatable disk, a valve stem pivotally connected to the angled portion of the shaft, and means for rotating 85 said shaft.

4. A device of the kind described comprising a discharge faucet, a valve seat, a valve movable toward and away from the seat, an electric switch comprising stationary contact 90 plates spaced apart, and a rotatable semi-circular contact plate adapted to slide upon the stationary plates and bridge the space between them, and common means for rotating the rotatable contact plate and moving the 95 valve as and for the purpose set forth.

ROBERT HARVEY McDOWELL.
